GUSTAV TER MEER, OF MUNICH, GERMANY, ASSIGNOR TO ALBERT T. OTTO & SONS, OF
NEW YORK, N. Y., A CORPORATION OF NEW YORK

DISCHARGING DEVICE FOR CENTRIFUGAL MACHINES

Application filed August 15, 1931, Serial No. 557,317, and in Germany June 10, 1930.

Certain features of this application are included in German applications filed July 1, 1930 and Aug. 20, 1930.

This invention relates to such baskets of centrifugal machines, which serve for the separation of solid materials from liquids or sludges and in which the solid materials are deposited in layers on the inner surface of the basket, from where they are removed after the completion of the separating process by means of a so-called scraping or peeling device without stoppage of the basket. As a rule such discharging device consists of a scraping or peeling knife, called a scraper, which is fitted either to a hinged bracket or a box-shaped carrier. The scraped-off material is allowed to drop on an inclined discharge spout or chute protruding into the basket or drum, on which it can slide out of the latter. Blockages are often encountered on centrifugal machines of this design at the discharge chute or in the scraper box, which leads to annoying interference with the smooth and continuous working of the machines. This drawback has its origin chiefly in the fact, that certain materials are of a viscous nature, thus liable to stick to the walls of the discharging device. The disturbing factor is further enhanced by the fact, that the scraped-off material is thrown fairly heavily against the walls of the discharging device owing to the revolving speed of the basket. Gradually the clear passage of the discharging device is choked until no further material can pass through the discharge spout or chute. The machine must then be stopped and the discharging device cleared. In order to facilitate the sliding-off of the scraped-off material from the discharging chute it would be the simplest way to make the incline of the chute as steep as possible, but the angle of the incline is limited for technical reasons. The above mentioned considerations have led to the employment of a worm conveyor for the emptying of a basket on various occasions. A discharging device on these lines proves however difficult to design and in consequence very costly. On the other hand a

worm conveyor cannot be employed in all cases, because materials of crystalline structure are easily destroyed by treatment of such kind.

One object of the present invention is to improve the first described discharging device. It provides principally means by which the discharging device or certain parts of it are vibrated during the discharging process, so that a sticking or clinging of the scraped-off materials is prevented. The vibration can be produced in various manners, as well as by various means. One possibility consists in the employment of a beating device, the knocker of which beats at short intervals against the members of the discharging appliance, which serve for the conveyance of the materials. As an important feature of the present invention, the knocker is automatically brought into operation when the scraping or peeling device is brought into cutting relationship with the solids accumulated on the inner periphery of the drum, and is automatically stopped when this device has moved to non-operating position.

Further information of the invention is given in detail below.

The accompanying drawings show various examples how the discharging device may be worked in accordance with the present invention; corresponding parts of the various figures are provided with similar reference characters.

Fig. 1 is a vertical longitudinal section through a centrifugal machine with a knocking device, driven by compressed air and acting upon the scraper carrier.

Fig. 2 shows a front elevation of a centrifugal machine after Figure 1.

Fig. 3 is a vertical longitudinal section through a centrifugal machine, on which a mechanical beating device or knocker acts upon the discharge chute or spout, which is arranged below the scraper carrier, and

Fig. 4 is a front elevation of the centrifugal machine in accordance with Figure 3, partly sectioned, partly in elevation.

Referring to Figures 1 and 2, 1 is the shaft of the centrifugal machine, running

in two bearings. Rigidly connected to the shaft is a basket or drum 2, into which the material to be treated is introduced through the charge pipe 3 of known design. The basket is surrounded by a casing 4. Inside the basket a scraping device is provided, consisting of a box-shaped scraper carrier or bracket 5 and a scraper 6, which extends nearly across the whole width of the basket and has its cutting edge facing the peripheral wall of the basket. The scraper carrier and scraper are movable in a vertical direction towards the shaft 1 of the machine, by means of a cross beam 7, extending laterally from the opening in the basket and supported by two guide columns 8. The cross beam 7 is connected to a rod 9, which carries at its top end a piston 10, which works inside a cylinder 11. Through the admission of a suitable pressure fluid, for instance pressure oil underneath the piston 10, the latter is moved in an upward direction. If the pressure fluid is however admitted above the piston 10 into the cylinder 11, the piston moves in a downward direction. As the piston 10 is rigidly connected with the scraping device, as stated above, the latter moves correspondingly with the piston. The scraping device however comes into action only after the separating period of the process is completed in the basket 2. For discharging the contents of the basket the scraper carrier or bracket 5 is moved at slow speed towards the peripheral wall of the basket, so that the scraper 6 comes in contact with the material deposited on the inside of the peripheral wall of the basket and gradually scrapes or peels the latter off whilst the basket is in motion. During this process the scraped-off material drops through the hollow scraper carrier 5 on the inclined discharge spout or chute 12, which protrudes into the basket 2, thus sliding off and out of the machine. In order to prevent the scraped-off material from sticking to the walls of the scraper carrier 5 and thus clogging gradually the passage through the said scraper carrier, blows are given at short intervals to the scraper carrier 5. For this purpose a pneumatic knocker 13 may be provided and supported for instance by the scraping device. The knocker may preferably be arranged within the hollow cross beam 7. The compressed air to work the knocker can be introduced by means of the flexible conduit 14. To regulate the number and intensity of the blows exerted by the device 13 to suit the material under treatment, a control member 15 is interposed in the conduit 14. As the knocker is operated only during the period of discharge its action is preferably made automatic in such manner, that the knocker is set going and stopped through the movement of the scraping device. For this purpose the compressed air

valve 16 can be provided with a bell crank 17, which acts in conjunction with a stop 18 on the cross beam 7 in such manner, that an upward movement of the scraping device opens the compressed air valve 16 and a downward movement of the cross beam closes the same. 70

It is obvious, that the knocker 13 can be actuated in some other manner, be it mechanically, electrically or otherwise, without deviating from the principal idea of this invention. 75

A mechanically operated knocker is shown as an example in the type as illustrated in Figures 3 and 4, wherein the knocker or beater acts upon the discharge chute 12 in contrast to the type described above. The knocker consists in this instance of a hammer-shaped body 18, the stem of which 19 is pivoted in the bearing 20. A spring 21, pressing upon the hammer stem, throws the knocker 18 against the lateral wall of the discharge chute 12. The lower end of the hammer stem 19, is under the control of a cam 22, so that its revolutions cause the knocker 18 to move away from the lateral wall 12 of the chute against the pressure of the spring 21. As soon as the raised portion of the cam 22 loses touch with the stem 19, the knocker 18 strikes the lateral wall of the discharge chute 12 95 under the action of the spring pressure, thus causing vibration in the discharge chute. This process is repeated at short intervals, as long as the cam 22 rotates in a clockwise direction as seen in Fig. 4. This rotation 100 is effected by a gear set 23. The drive of the gear set and thereby of the knocker is automatic, because this device is connected with the cross beam 7 of the scraping device through the rod 24, whose lower portion is 105 shaped as rack, meshing with one of the gears of the gear set 23. As soon as the scraping device comes into action by being moved in an upward direction, the gears of the set 23 are rotated through the rod 24, which moves 110 in an upward direction also.

Any suitable means may be provided for preventing interference of the cam 22 and the hammer lever 19 during lowering of the scraper. For instance, a unidirectional clutch may be positioned between the gear which meshes with the rack rod 24 and the shaft upon which said gear is mounted, this clutch driving said shaft in a counterclockwise direction as shown in Fig. 4, but permitting said gear to rotate idly around said shaft in a clockwise direction. Instead of such clutch the lower end portion of the hammer lever may be connected to the body of the lever by a knee joint permitting said lower 125 portion to swing only in a clockwise direction.

It is obvious, that this invention is not restricted to the types shown in the drawings. It is for instance possible without any diffi- 130

culties to form the shaking viz knocking device and its drive in a different manner. The idea of the invention bases rather on the fact, that parts of the discharge device are subjected to vibration, so that a sticking or clinging of the scraped-off material to the same is avoided.

Having thus described my invention, what I claim as new and desire to protect by Letters Patent is:

1. A centrifugal machine, including a rotatable separating drum having a peripheral wall adapted to collect the separated solids, a scraper inside of said drum and movable into and out of scraping relationship with the peripheral wall, an inclined wall below said scraper and onto which the scraped solids fall, a knocker for rapping on said wall to vibrate the latter and loosen material which may adhere thereto, and connections between said scraper and said knocker for operating said knocker upon movement of said scraper into operating position.

2. A centrifugal machine, including a rotatable separating drum having a peripheral wall on which separated solids collect, a scraper inside of said drum and movable into and out of scraping relationship with the peripheral wall, a chute positioned under said scraper for conducting the scraped solids from the drum, a knocker vibrating said chute and loosening material which may adhere thereto, and means controlled by the movement of said scraper for controlling the operation of said knocker.

3. A centrifugal machine, including a separating drum having a peripheral wall for the collection of separated solids, a scraper inside of said drum and movable toward and from said wall, a chute below said scraper, a knocker adapted to vibrate against said chute for releasing material which may adhere thereto, means operated by the movement of said scraper into operating position for controlling the operation of said knocker, and means for rendering said knocker inoperative upon movement of said scraper away from its operative position.

4. A centrifugal machine, including a rotatable separating drum having a peripheral wall, a scraper within said drum, means for moving said scraper into and out of scraping relationship with said peripheral wall, an inclined wall disposed under the scraper for carrying off scraped material from the region near said scraper, a pneumatic knocker, a valve for controlling the operation of said knocker, and means operated by the movement of said scraper into and out of scraping relationship with said peripheral wall for opening and closing said valve.

5. A centrifugal machine, including a separating drum open at one end and having a peripheral wall on which the separated solid

material is collected, a scraper inside of said drum, an inclined wall within said drum and under the scraper for directing the scraped off material toward said open end, a pair of spaced guide columns on the outside of said drum adjacent to the open end of the drum, a cross beam engaging said guide column and connected to said scraper, means for moving said cross beam along said columns to bring the scraper into or out of cutting relationship with the material to be scraped, a knocker carried by said cross beam and adapted to operate on said chute, and means controlled by the movement of said cross beam for controlling the operation of said knocker.

6. A centrifugal machine, including a separating drum having a peripheral wall, a scraper inside of said drum and movable toward and away from said wall, a chute positioned under the scraper for receiving the scraped material, a pivoted hammer adjacent to said chute, a spring for forcing said hammer into contact with said chute, a cam for moving said hammer in the opposite direction, and means operated by the movement of said scraper towards said peripheral wall for rotating said cam to oscillate said hammer about its pivot point whereby said hammer intermittently strikes said chute.

7. A centrifugal machine, including a separating drum having a peripheral wall on which separated solids collect, a scraper inside of said drum, a chute positioned under the scraper, a member on the outside of said drum adjacent to its open end, connected to the scraper, and movable to bring the scraper into or out of scraping relationship with said peripheral wall, a hammer adjacent to said chute for striking the latter, a cam for oscillating said hammer about its pivot point, a rack connected to said member for movement therewith, and gearing for transmitting movement from said rack to said cam upon movement of said member.

8. A centrifugal machine, including a separating drum open at one end and having a peripheral wall on which separated solids are adapted to be collected, a scraper inside of said drum, a member outside of said drum adjacent to its open end, movable in a vertical direction and connected to said scraper, a chute having an inclined surface positioned under the scraper, a hammer pivotally connected between the ends thereof to the outside of said chute, and having one end thereof adapted to come in contact with the walls of said chute, a spring for urging said end of said hammer in contact with the walls of said chute, a cam engaging the other end of said hammer, and means for transmitting rotary movement to said cam from said member upon upward movement of said member.

GUSTAV TER MEER.
